DRIVING SYSTEM FOR LOUD SPEAKERS

Application filed October 20, 1930, Serial No. 490,066, and in Germany October 22, 1929.

The invention has for its object the provision of a driving system for loudspeakers, which is efficient and easy to manufacture.

The driving system is of the type having 5 a soft iron armature and two or more coils energized by the alternating current, a magnetic field being developed in the armature and in the magnetic material carrying the alternating fluxes of the coils by a polarizing magnet characterized in that the armature is shaped as a cylindrical rod and is mounted in and moves in the direction of the common axis of the coils.

According to a feature of the invention 15 the magnetic circuits of the alternating current coils are mutually independent and these circuits are influenced in opposite senses when the armature is displaced.

According to another feature of the invention the armature, coils and pole pieces of 20 the magnet are cylindrical and coaxial with the armature.

An object of the invention is the provision of a loudspeaker driving system which 25 is freely supported on ball bearings at its extremity and is movable in both directions without being subjected to a restraining force, which might result in a high inherent frequency of the oscillating armature.

Still another object of the invention is a 30 method of constructing ball bearings suitable for this purpose. According to this method a cylindrical mantle having a collar and an inner diameter greater than that of 35 the armature spindle and fitting with its outer diameter in an opening of the housing is bored with a number of longitudinal holes, corresponding to the number of balls whose diameter is smaller than that of the holes.

The operation of boring cuts through the 40 outer surfaces of the mantle, so that slits are formed, through which the balls contact with the casing and with the spindle. The 45 borings are afterwards shut off by means of props.

The invention will be explained in connection with the constructions shown by way of example in the annexed drawings.

Figures 1 and 2 show one form of con-

struction of the driving system according to the invention.

Figures 3 and 4 show a modified form of construction.

Figures 5 and 6 show in detail a ball bearing 55 for a driving system according to the invention.

Figure 7 shows a detail.

The driving system according to Figures 1 and 2 consists of a cylindrical hollow polarizing magnet 15 having pole shoes 41. Two ring shaped alternating current coils 6 and 7 are disposed in casings 4 and 5 placed coaxially within the polarizing magnet. The casings 4 and 5 which surround 60 the coils 6 and 7 on three sides and are to this end constituted by two flat side rings and a circumferential cylindrical ring are constructed of magnetic material and are separated by a distance piece 32 of non- 65 magnetic material. The casings contact at their outward flat surfaces with the pole 70 shoes 41 of the permanent magnet.

Inside of the annular casings 4 and 5 the rod-shaped armature 17-21 is mounted in 75 ball bearings 39 fixed inside the pole shoes of the polarizing magnet. The armature consists of a core 21 of non-magnetic material on the middle part of which is clamped a sleeve 17 of magnetic material. This 80 sleeve rests with one end against a ring on the core and is held in position by a nut 40 screwed tight against its other end. The sleeve 17 is formed with two annular parts at the ends, joined by a thinner shaftlike 85 portion. The annular parts are slightly greater in width than the coils, in which they fit with as small a clearance as possible.

Instead of a permanent cylindrical polarizing magnet an electromagnet or a magnet 90 of non-cylindrical form may be used.

Both end surfaces of the apparatus are covered with plates 42, preferable of insulating material.

The coils of the driving system may be 95 connected in series or in parallel.

The ball bearings in which the armature core rests, may be constructed as shown in Figures 5 and 6. According to these figures the main part is a cylindrical mantle 35 hav-

ing a collar 37. In this mantle a number of holes 36 is bored, forming slits where they pierce the outer surface of the mantle. After introduction of the balls 20 the borings are closed by plugs 38, the slits being so narrow, that the balls cannot fall out. The mantle is now introduced into a central boring of the pole shoe. The balls then contact on the outside with the metal of the pole shoe or with a hardened ring introduced for the purpose and on the inside with a steel ring placed on the armature core in Figures 1 and 2 or directly with the armature spindle in Figures 3 and 4.

15 The armature transmits its movement to a loudspeaker diaphragm or similar apparatus by means of a rod 14 fixed to the armature core.

In operation the polarizing flux flows from 20 one pole of the polarizing magnet through the coil casing and the corresponding annular part of the armature; thence through the armature shaft to the other annular part and the second coil casing to the other pole.

25 Around every coil this flux is modified by the speaking currents flowing in the coils in such a way, that north and south poles are generated, which exert attractive and repulsive forces, that tend to move the armature 30 in a longitudinal direction. It should be noted, that the coils should be interconnected in such a way, that the forces exerted on the armature have the same direction for both coils.

35 When the armature moves, the path followed by the polarizing flux is modified, so that back electromotive forces are generated in the coils.

The construction of Figures 3 and 4 differs only from that just described, in that 40 the armature sleeve is mounted on a spindle of non-magnetic steel 21, thus permitting a reduction in diameter and simplifying the construction of the ball bearings.

45 In all other respects this construction is equal to that of Figures 1 and 2.

According to the modification represented 50 in Figure 7 the inner edges of the sides of the coil casings and the annular parts of the armature are formed with sharp edges as at 44. Thereby the induction at these points is increased and the electro-mechanical effect of the driving system is improved. The 55 relative position of the sharp edges of the armature and the coil casings is about the same as that of the square-edges in the other constructions.

It should be clear, that the driving systems may be modified without departing 60 from the principle of the invention.

What we claim is:

1. Driving system for a loudspeaker, comprising an armature of magnetic material, a plurality of driving coils, a casing of magnetic material for each of the coils, a polar-

izing magnet in the magnetic circuit of which the armature and the casings of magnetic material surrounding the coils is included, the armature being shaped substantially as a cylinder and being supported slidably in 70 the common axis of the coils the air gaps between the armature and the magnetic material carrying the alternating fluxes of the coils remaining constant and the direction of the polarizing flux in the armature being 75 substantially parallel to this axis.

2. Driving system for a loudspeaker, comprising an armature of magnetic material, a plurality of driving coils, a polarizing magnet in the magnetic circuit of which is successively included the fixed magnetic material carrying the alternating flux of one of the coils, the armature and the magnetic material carrying the alternating flux of the other coil, the armature being shaped as a cylinder 80 and being adapted to slide in the direction of the axis of the coils, the direction of the polarizing flux in the armature being substantially parallel to this axis.

3. Driving system for a loudspeaker comprising an armature of magnetic material, a plurality of driving coils, each having an enclosing casing of magnetic material having mutually independent paths for their 85 alternating fluxes, a polarizing magnet in the magnetic circuit of which the armature casings of magnetic material carrying these fluxes are included, the armature, which is substantially cylindrical being supported 90 slidably in the common axis of the coils and adjoining with its respective extremities the pole pieces of the polarizing magnet.

4. Driving system for a loudspeaker comprising an armature of magnetic material, a plurality of driving coils, a polarizing magnet in the magnetic circuit of which is successively included one coil with its fixed magnetic material, the armature and the other coil with its magnetic material, the armature 10 consisting of two bosses joined by a thinner shaft and being adapted to slide in the direction of the axis, the coils having mutually independent paths for their alternating fluxes, the polarizing flux entering the armature at one of the bosses and leaving it at 11 the other.

5. Driving system for a loudspeaker comprising an armature of magnetic material, a plurality of driving coils, a polarizing magnet in the magnetic circuit of which the armature and the coils are included the armature being substantially cylindrical and being supported slidably in the common axis of the coils, the coils being cylindrical 12 and coaxial with the armature and substantially of equal size.

6. Driving system for a loudspeaker comprising a soft iron armature, a plurality of driving coils, each having an enclosing iron casing, a polarizing magnet in the magnetic 13

circuit of which the armature and the iron casings of the coils are included, the armature being substantially cylindrical and being supported slidably in the common axis 5 of the coils, the coils and the pole pieces of the magnet being cylindrical and coaxial with the armature, the polarizing magnet having the form of a cylindrical mantle, and the polarizing field being substantially of the 10 same shape at both ends of the said mantle.

7. Driving system for a loudspeaker comprising an armature of magnetic material, arranged at its extremities in ball bearings, a plurality of driving coils, a polarizing magnet in the magnetic circuit of which the armature 15 and the magnetic material carrying the alternating fluxes of the coils is included, the armature being substantially cylindrical and being supported slidably in the common axis 20 of the coils.

8. Apparatus of the class described, comprising a casing forming a magnet and having pole pieces at its opposite ends, an armature arranged in the magnetic casing and mounted for reciprocating longitudinal movement, said armature comprising a non-magnetic substantially cylindrical core and a magnetic substantially cylindrical sleeve on said core, and a pair of coils through the 25 centers of which the armature extends, said coils having casings of magnetic material arranged on the respective pole pieces.

In testimony whereof we have signed our names to this specification.
